SURVEYOR'S ILLUMINATED BACKSIGHT

Frederick J. Skrastin, Jr., Butte, Mont.

Application August 13, 1948, Serial No. 44,032

4 Claims. (Cl. 240—6.4)

1

This invention relates to an illuminated backsight for use by surveyors in night surveying work or when surveying in unilluminated places like mines, tunnels, and the like, the primary object of the invention being to provide a practical and efficient self-luminous backsight upon which the cross hairs of the transit telescope can be easily centered from different remote locations around the sides of the backsight, the backsight being adapted to be suspended at a known point in the area to be surveyed, so that surveyors can measure the angle between the backsight and the next station.

Another important object of the invention is to provide a compact and serviceable device of the character indicated above which provides a white luminous background for the black cross hairs of the telescope of the surveyor's transit, thereby affording easier centering of the cross hairs on the backsight.

Another important object of the invention is the provision of a device of the above indicated character having a luminous sight head of transparent plastic capable of internal transmission of light supplied to the head from an electric bulb energized by dry batteries contained in the device, whereby visibility of the device is enhanced and whereby the sight marks within the head are made to stand out in contrast to the head.

Other important objects and advantageous features of the invention will be apparent from the following description and accompanying drawings, wherein merely for present purposes of illustration, a specific embodiment of the invention is set forth in detail.

In the drawing:

Figure 1 is a contracted transverse vertical section taken through the illustrated device.

Figure 2 is a side elevation of the upper part of the device, and

Figure 3 is a top plan view thereof.

Referring in detail to the drawings, the numeral 5 designates the elongated preferably brass tube constituting the body or casing of the illustrated device, the upper and lower ends being internally threaded, as indicated at 6 and 7, respectively. Into the lower end of the casing is threaded the boss 8 on a dome-shaped, preferably brass cap 9, having a threaded axial bore 10, through which is threaded the brass switch screw 11 having a squared lower end 12 formed with a key-hole opening 13 to receive a key or tool (not shown) for turning the screw and to enable attaching metal weights when needed in windy places. The screw can be turned up to put the upper end of the screw 11 through an insulator disk 14 to engage the lower end of the lowermost

2

of a plurality of dry cells 15, such as flashlight batteries, confined thereabove in the casing 5, and thereby close the bulb circuit of the device.

Positioned in the casing 5 above the uppermost dry cell 15 is an insulated washer 16 having a central hole 17 through which the center terminal 18 of the uppermost dry cell is exposed. Resting upon the washer 16 is the cylindrical brass bulb holder and reflector 19 having a threaded axial bore 20, opening at its lower end in a concave recess 21 and at its upper end in a polished or reflector-coated frusto-conical depression 22 constituting the reflector for the bulb 23, which is threaded in the bore 20 with its base contact 24 engaged with the terminal 18 of the uppermost dry cell 15. In this arrangement the ferrule 25 of the bulb is in contact with the brass casing 5 with the bulb base contact 24 in contact with the dry cell terminal 16, so that contacting of the screw 11 with the case of the lowermost dry cell 15 closes the circuit and illuminates the bulb 23.

Threaded into the upper end 6 of the casing 5 is the threaded lower portion 26 of the cylindrical sighthead 27, the lower portion 26 engaging the upper end of the combined bulb holder and reflector 19, thereby holding this and the dry cells 15 in place in the casing 5.

The sight head 27 is formed with an axial conical depression 28 in its upper end which terminates in a shallow cylindrical internally threaded portion 29 into which is threaded a flat plug 30 to a position flush with the upper end of the head. A brass stud 31, threaded axially in the plug 30, has a key-hole opening 32 in its upper end to accommodate by sidewise insertion therein the lowermost bead 33 of a flexible bead chain 34, the bead 33 being retained in the opening 32 by a removable brass cap 35 on the stud 31. The uppermost bead 36 of the chain 34 is similarly associated with a stud 37 having a key-hole 38 accommodating this bead, and a removable retaining cap 39, the upper end of the stud 37 being transversely apertured at 40 to accommodate a slip ring 41 by which the device is suspended for use from a suitable overhead support (not shown).

The sight head 27 is made of transparent plastic able to transmit and reflect light internally which is impinged on its lower end from the bulb 23 and the reflector 22, various materials, such as acrylic and methacrylic plastics, being suitable. The walls of the conical depression 28 are disposed at an angle of 45° to the axis of the head so as to reflect outwardly through the sides of the head light rays transmitted upwardly therein from the bulb 23 and thereby increase the luminosity of the head 27 and increase the illumination and visibility of the upper and lower

sight marks 42 and 43 respectively, which are arranged axially in the head 27 in line with the center of the depression 28 and the chain 34. The plug 30 is of the same material as the head 27.

The upper sight mark 42 is axially aligned with but longer in diameter than the lower sight mark 43. These sight marks being of substantially the same length, with the upper end of the upper mark at the apex of the depression 28, and the lower end of the lower mark at the upper end of the casing 5. The sight marks are constituted by bores formed in the head 27 in which light from the bulb 23 and reflected and transmitted within the head 27 concentrates to provide highly illuminated marks contrasting by their brilliance with the relatively faint luminosity of the remainder of the head 27. The larger upper sight mark 42 is for long distance work and the smaller lower mark 43 for short distance work.

The light rays from the bulb 23 and reflector 22 travel upwardly through the head 27 until the light rays are reflected laterally outwardly through the sides of the head 27 by the polished conical reflector depression 28. With this arrangement and the bulb 23 alight, a brilliant concentrated light streak is produced comparable to that seen when observing a flashlight head on. It is this brilliant streak which the surveyor is able to see at long distances from the backsight when not in focus. It appears as a light blur until properly focussed by the surveyor when it appears as a thin streak of brilliance.

The sight works 42, 43 are drilled out and are highly scratched to produce a contrast effect with the head 27. The sight work 42 may be formed with a fine thread to produce a contrast with the luminous head 27.

What is claimed is:

1. A luminous surveyor's backsight comprising a cylindrical translucent head having an upper end and a lower end, a tubular casing secured to depend from said lower end, illuminating means in said casing to direct light upwardly through the lower end of said head, an axial bore formed in said head providing a luminous sight mark when illuminated by said means, said upper end of said head being formed with an axial recess having internal screw threads at its upper end, a disk threaded into the upper end of said head, and suspending means secured to said disk.

2. A luminous surveyor's backsight comprising a cylindrical translucent head having an upper end and a lower end, a tubular casing secured to depend from said lower end, illuminating means in said casing to direct light upwardly through the lower end of said head, an axial bore formed in said head providing a luminous sight mark when illuminated by said means, said upper end of said head being formed with an axial recess having internal screw threads at its upper end, a disk threaded into the upper end of said head, and suspending means secured to said disk, said disk closing the upper end of said recess, said recess being substantially larger in diameter than said bore and inverted conical in form providing a circular upwardly flaring wall acting in conjunction with the underside of said disk to reflect light from said bore and light passing upwardly through said head in downward and laterally outward directions.

3. A luminous surveyor's backsight comprising a luminous head formed of transparent material capable of internal transmission and reflection of light rays impinged upon one end thereof, axially extending means in said head arranged

to be illuminated to greater brilliance than the remainder of said head by light rays impinged thereon to provide sight mark means, a tubular casing secured to depend from the lower end of said head, a bulb reflector in said casing immediately below and facing the lower end of said head, an electric bulb mounted in said reflector whereby light rays from said bulb and from said reflector are impinged upon the lower end of said head when said bulb is energized, battery means within said casing below said reflector, a cap on the lower end of said casing retaining said battery means in said casing, switch means having an operating member on said cap for connecting said bulb in circuit with said battery means to energize said bulb, and means connected to the upper end of said head in axial alignment with said sight mark means for suspending said backsight from an overhead support, the upper end of said head being formed with an axial conical depression acting as a reflector to reflect laterally outwardly within said head light rays transmitted upwardly through said head from said bulb for intensifying the luminosity of said sight mark means.

4. A luminous surveyor's backsight comprising a luminous head formed of transparent material capable of internal transmission and reflection of light rays impinged upon one end thereof, axially extending means in said head arranged to be illuminated to greater brilliance than the remainder of said head by light rays impinged thereon to provide sight mark means, a tubular casing secured to depend from the lower end of said head, a bulb reflector in said casing immediately below and facing the lower end of said head, an electric bulb mounted in said reflector whereby light rays from said bulb and from said reflector are impinged upon the lower end of said head when said bulb is energized, battery means within said casing below said reflector, a cap on the lower end of said casing retaining said battery means in said casing, switch means having an operating member on said cap for connecting said bulb in circuit with said battery means to energize said bulb, and means connected to the upper end of said head in axial alignment with said sight mark means for suspending said backsight from an overhead support, the upper end of said head being formed with an axial conical depression acting as a reflector to reflect laterally outwardly within said head light rays transmitted upwardly through said head from said bulb for intensifying the luminosity of said sight mark means, a transparent plug closing the upper end of said conical depression, said suspending means being supportably connected with said plug for suspending the backsight.
